Filed Mar. 22, 1965, Ser. No. 84,378

Term of patent 14 years

(Cl. D62—4)

FIG. 1

FIG. 2

FIG. 3

FIG. 4

FIGURE 1 is a perspective view of the centrifugal fan showing the front and one side of my new design;

FIGURE 2 is a side elevation of the centrifugal fan showing the other side thereof;

FIGURE 3 is a top view of the centrifugal fan shown in FIGURES 1 and 2; and

FIGURE 4 is a perspective view of the centrifugal fan from an angle opposite to that of FIGURE 1 showing the back and other side of my new design.

The characteristic features of my design reside in the specific configuration of the motor housing combined with the blower unit as shown.

I claim:

The ornamental design for a centrifugal fan, as shown and described.
